Primary Examiner — Catherine Tuttle(74) Attorney, Agent, or Firm — Tsz Lung Yeung(57) CLAIM

The ornamental design for a net set for sports, as shown and described.

DESCRIPTION

FIG. 1 is a perspective view of a net set for sports showing my new design.

FIG. 2 is a front view thereof.

FIG. 3 is a rear view thereof.

FIG. 4 is a right end view thereof.

FIG. 5 is a left end view thereof.

FIG. 6 is a top view thereof; and,

FIG. 7 is a bottom view thereof.

The broken lines are included for the purpose of illustrating the portions of the net for sports that form no part of the claimed design.
